UNITED STATES PATENT OFFICE.

FRANCIS H. BUZZACOTT, OF CHICAGO, ILLINOIS.

DESIGN FOR A RANGE-GRADE.

SPECIFICATION forming part of Design No. 34,415, dated April 23, 1901.

Application filed March 18, 1901. Serial No. 51,783. Term of patent 7 years.

To all whom it may concern:

Be it known that I, FRANCIS H. BUZZACOTT, a citizen of the United States, residing at Chicago, in the county of Cook and State of Illinois, have invented and produced a new and original Design for a Range-Grate, of which the following is a specification, reference being had to the accompanying drawings, forming a part hereof.

Figure 1 is a view in side elevation of a range-grate of my new and original design; Fig. 2, a bottom plan view of said grate; Fig. 3, a vertical longitudinal section taken as indicated at line 3 of Fig. 2; Fig. 4, a view in end elevation, the end adjacent to the fire-door being presented; and Fig. 5, a transverse section taken as indicated at line 5 of Fig. 2.

As shown in the drawings, the leading or material feature of my design consists in the basket-form grate A, having lateral flanges a , recessed at points a' , vertical recesses a^2 at the sides of the grate, vertical recesses a^3 at

the ends of the grate, longitudinal recesses a^4 at the base of the grate, and transverse ribs a^5 crossing the recesses a^4 . The ribs a^5 are shown to project beneath the longitudinal ribs formed between the slots a^4 . One end of the grate is represented at A' and the other at A², the former being of the same height as the body of the grate and the latter of less height.

Having described my invention, what I claim as new, and desire to secure by Letters Patent, is—

The design for a range-grate, as herein shown and described.

In testimony whereof I have signed my name to this specification in the presence of two subscribing witnesses.

FRANCIS H. BUZZACOTT.
